LIGHTING LUMINAIRE

**CROSS-REFERENCE TO PRIOR
APPLICATIONS**

This application is the U.S. National Phase application under 35 U.S.C. § 371 of International Application No. PCT/EP2022/080097, filed on Oct. 27, 2022, which claims the benefit of European Patent Application No. 21205759.0, filed on Nov. 1, 2021. These applications are hereby incorporated by reference herein.

TECHNICAL FIELD

The disclosure relates to a lighting luminaire, in particular for a suspended tile light ceiling assembly. Such lighting luminaires are in essence composed of an elongated fixture housing comprising an elongated light exit opening and an elongated light exit window plate, functioning as a light diffusor plate, and structured to be mounted to the fixture housing for covering the elongated light exit opening. Next to the application of such lighting luminaire in a suspended tile light ceiling assembly, such lighting luminaire can also be used in an illumination system for line illumination, wherein such illumination system for line illumination is composed of multiple lighting luminaires connected in line with each other, thereby forming a self-sustained trunked illumination system.

BACKGROUND OF THE DISCLOSURE

A lighting luminaire as outlined above, either used as a standalone light unit or in a suspended tile light ceiling assembly or in a trunked illumination system suited for line illumination, is commonly known and finds general application in illuminating large room areas, in particular office spaces, retail spaces (supermarkets), manufacturing areas, warehouses, distribution centres, etc. etc. Such lighting luminaires are composed of an elongated fixture housing and a corresponding elongated light exit window plate or light diffuser plate. Both parts can have a considerable length of 1000 mm or more.

The diffuser plates used in such lighting luminaires are typically manufactured in two ways. They are either cut from larger sheets of plastic material or are manufactured using extrusion techniques. Sheet cut diffuser plates and extruded diffuser plates can have lengths of 1000 mm and above up to 3500 mm. Whereas sheet cut diffuser plates have a flat configuration, extruded diffuser plates can be manufactured with a three-dimensional surface profile for additional light diffusing effects. Sheet cut diffuser plates are relatively inexpensive to manufacture as no significant tool investments are required, whereas extruded diffuser plates require specific machinery including a specific design of an extrusion die. A sheet cut diffuser plate requires either a simple assembly to the elongated fixture housing by means of sliding in, or with the use of additional fixing parts, for example screws or brackets. Extruded diffuser plates can also be slid-in, but the extruded profile of the plate has usually a snap interface, that snaps with the fixture housing.

Sliding in a sheet cut diffuser plate or an extruded diffuser plate element having lengths of 1000 mm or more is cumbersome on the assembly line as it doubles the footprint of the assembly table. Also the on-site replacement of a slide-in diffusor plate of an already installed lighting luminaire is equally cumbersome and complex. In addition, an

2
extruded diffuser plate requires tooling and high-volume production batches for being cost-effective.

In addition, the above known examples of a lighting luminaire require high manufacturing tolerances of both the fixture housing as well as the diffuser plate. It is thus desirable to present a lighting luminaire, which is easy to assembly and disassembly not requiring high manufacturing tolerances.

U.S. Pat. No. 7,758,207B1 discloses a lightweight LED lamp.

SUMMARY OF THE DISCLOSURE

The disclosure proposes a lighting luminaire, in particular for a suspended tile light ceiling assembly, the lighting luminaire at least comprising an elongated fixture housing comprising an elongated light exit opening; and an elongated light exit window plate structured to be mounted to the fixture housing for covering the elongated light exit opening, wherein the elongated light exit opening is bound by two longitudinal mounting slots facing each other, the longitudinal mounting slots each being configured to accommodate a longitudinal plate edge of the elongated light exit window plate, wherein the elongated light exit window plate has a width larger than a width of the elongated light exit opening, but smaller than a distance between longitudinal mounting slots facing each other, and the lighting luminaire further comprising a set of two fixating plate elements, each fixating plate element having two longitudinal element edges each structured to be accommodated in one of the two longitudinal mounting slots and a frontal element edge structured to fixate the elongated light exit window plate between the two longitudinal mounting slots through abutment against a frontal plate edge of the elongated light exit window plate.

The frontal element edge is further structured to fixate and center the elongated light exit window plate between the two longitudinal mounting slots in a cross direction transverse to a longitudinal direction through abutment against both longitudinal plate edges of the elongated light exit window plate, thus fixating and centering the elongated light exit window plate relative to the mounting slots, and accordingly providing a proper covering of the light exit window.

Accordingly, as the elongated light exit window plate or diffuser plate has a width larger than a width of the elongated light exit opening, but smaller than a distance between longitudinal mounting slots facing each other, an easy top-down mounting by means of tilting of the elongated light exit window plate in the elongated fixture housing is possible, and the usual sliding in technique is no longer necessary. The assembly of such lighting luminaire is less cumbersome, either at the assembly line (which now can have a reduced footprint) as well as on-site for maintenance or replacement purposes. Fixating the elongated light exit window plate or diffuser plate through abutment at their frontal plate edge with the two fixating plate elements prevents a dislodging of the diffuser plate from the longitudinal slots, which bound the light exit window without the use of additional fixing parts, for example screws or brackets. Also it is not necessary to design and manufacture diffuser plates with complex snap fit interfaces by means of extrusion.

In a preferred example, the fixating plate element has a width larger than the width of the elongated light exit window plate, but a width smaller than the distance between the longitudinal mounting slots facing each other. Accordingly, this allows a proper centering of the elongated light exit window plate between the longitudinal mounting slots,

ensuring an overall covering of the light exit window without exposed light slits. It also prevents an undesired dislodging of the elongated light exit window plate from the longitudinal mounting slots and from the lighting luminaire accordingly.

In a particular example, the fixating plate element has a width equal to the distance between the longitudinal mounting slots facing each other, also further guaranteeing a proper centering of the fixating plate element within the slots and relative to the elongated light exit window plate.

Preferably, the fixating plate element has a profiled frontal element edge that is complementary shaped to a profiled frontal plate edge of the elongated light exit window plate, thus forming mutually matching profiles. For example, the profiled frontal element edge or the profiled frontal plate edge is partly or fully convexly profiled and the profiled frontal plate edge or the profiled frontal element edge is complementary concavely profiled. This ensures a proper abutment over the full width dimension of both the elongated light exit window plate and the interacting fixating plate element, thus guaranteeing the fixating and centering relative to the mounting slots.

In particular, the profiled frontal element edge and the profiled frontal plate edge are symmetric along a longitudinal direction of either fixating plate element and elongated light exit window plate. Herewith the assembly of both the fixating plate elements and the elongated light exit window plate is simplified, and its mounting can be achieved irrespective of their side orientation.

In an example, the profiled frontal element edge or the profiled frontal plate edge is provided with at least two (convex) protrusions and the profiled frontal plate edge or the profiled frontal element edge is provided with at least two complementary (concave) recesses.

For cost effective reasons as well for ensuring uniform optic features, the fixating plate element and the elongated light exit window plate are made from the same light transmissive material. Accordingly, the light emission from the lighting luminaire is not different for the separate elements, which cover the light exit window, further improving its overall appearance to a user.

The lighting luminaire further comprises at least one light emitting element accommodated in the elongated fixture housing, the elongated fixture housing is provided with power electronics for supplying power to the at least one light emitting element.

The disclosure also pertains to a kit of parts comprising an elongated light exit window plate and at least two fixating plate element according to the disclosure.

BRIEF DESCRIPTION OF THE DRAWINGS

The disclosure will now be discussed with reference to the drawings, which show in:

FIG. 1 a non-exemplary example of a lighting luminaire according to the disclosure;

FIGS. 2-8D various details of non-exemplary examples of a lighting luminaire according to the disclosure.

DETAILED DESCRIPTION OF THE DRAWINGS

For a proper understanding of the disclosure, in the detailed description below corresponding elements or parts of the disclosure will be denoted with identical reference numerals in the drawings.

The disclosure proposes in FIG. 1 a lighting luminaire, which is denoted with reference numeral 10. The lighting

luminaire 10 is disclosed in this description in a non-exemplary manner. In this particular example, the lighting luminaire 10 is configured as an elongated plate shaped tile luminaire for use a suspended tile light ceiling assembly (not shown). However, a lighting luminaire according to the disclosure above can also be used as a standalone light unit or in a trunked illumination system suited for line illumination. Such lighting luminaires are commonly known and find general application in illuminating large room areas, in particular office spaces, retail spaces (supermarkets), manufacturing areas, warehouses, distribution centres, etc. etc. In general, these lighting luminaires are composed of an elongated fixture housing and a corresponding elongated light exit window plate or light diffuser plate. Both parts can have a considerable length of 1000 mm or more.

The present disclosure, and in particular the non-exemplary example of FIG. 1 and its detailed views of FIGS. 2-8, proposes a lighting luminaire, which is easy to assembly and disassembly not requiring high manufacturing tolerances.

Returning to FIG. 1 and also referring to the FIGS. 2-8 for additional details, the non-exemplary example of the lighting luminaire 10 is composed of an elongated fixture housing 11. The elongated fixture housing 11 is formed as a U-profile having a base part 11c and first and second side parts 11a and 11b. The first and second side parts 11a and 11b form the legs of the U-profile and enclose a chamber or space in which one or more light emitting elements 12 are accommodated. The one or more light emitting elements or light emitting sources 12 are mounted on a substrate 21 in the elongated fixture housing 11. Power electronics or power circuitry 13 are provided for supplying electric power to the at least one light emitting element 12.

The elongated fixture housing 11 furthermore comprises an elongated light exit opening 14, allowing light being emitted by the light emitting element 12 to leave the space formed by the U-profiled elongated fixture housing 11. The elongated light exit opening 14 is bound by two longitudinal mounting slots 15a and 15b, which are each part of the first and second side parts 11a and 11b, respectively of the U-profiled elongated fixture housing 11.

The two longitudinal mounting slots 15a and 15b are each formed of two flanges 15a1-15a2 (15b1-15b2) extending parallel and at some distance from each other. Each longitudinal mounting slot 15a and 15b has a base face 15a3 and 15b3. The two flanges 15a1-15a2 (15b1-15b2) of each mounting slot 15a (15b) are orientated in the plane of the elongated light exit opening 14, and accordingly the mounting slots 15a-15b (base faces 15a3-15b3) are facing each other.

The distance between the two flanges 15a1-15a2 (15b1-15b2) of each mounting slot 15a (15b) is such that each longitudinal mounting slot 15a and 15b is capable in accommodating a first and second longitudinal plate edge 16a and 16b respectively of an elongated light exit window plate 16, see FIGS. 1, 4, 5, 6 and 7. The distance between the two flanges 15a1-15a2 (15b1-15b2) is slightly larger than a thickness of the elongated light exit window plate 16.

The elongated light exit window plate 16 functions as a light diffuser plate and is mounted to the fixture housing 11 as outlined above. Accordingly, the light diffuser plate 16 covers the elongated light exit opening 14 and provides diffused light for effectively illuminating the office space, the retail space (supermarket), manufacturing area, warehouse, or distribution centre, etc. etc., in short the area in which the lighting luminaire 10 is installed.

Known, prior art diffuser plates used in lighting luminaires are typically manufactured in two ways. They are

either cut from larger sheets of plastic material or are manufactured using extrusion techniques. Sheet cut diffuser plates and extruded diffuser plates can have lengths of 1000 mm and above up to 3500 mm. Whereas sheet cut diffuser plates have a flat configuration, extruded diffuser plates can be manufactured with a three-dimensional surface profile for additional light diffusing effects. Sheet cut diffuser plates are relatively inexpensive to manufacture as no significant tool investments are required, whereas extruded diffuser plates require specific machinery including a specific design of an extrusion die. A sheet cut diffuser plate requires either a simple assembly to the elongated fixture housing by means of sliding in, or with the use of additional fixing parts, for example screws or brackets. Extruded diffuser plates can also be slid-in, but the extruded profile of the plate has usually a snap interface, that snaps with the fixture housing.

Sliding in a sheet cut diffuser plate or an extruded diffuser plate element having lengths of 1000 mm or more is cumbersome on the assembly line as it doubles the footprint of the assembly table. Also the on-site replacement of a slide-in diffuser plate of an already installed lighting luminaire is equally cumbersome and complex. In addition, an extruded diffuser plate requires tooling and high-volume production batches for being cost-effective.

The proposed lighting luminaire according to the disclosure is easy to assembly as well as to disassembly not requiring high manufacturing tolerances. Accordingly, the elongated light exit window plate 16 has a width 16z, which is larger than a width 14z of the elongated light exit opening 14, but smaller than a distance 15z between the first and second longitudinal mounting slots 15a-15b facing each other. With reference to FIG. 5, distance 15z is defined as the distance between the two base parts 15a3 and 15b3 of the longitudinal mounting slots 15a-15b facing each other.

Accordingly, distance 14z<distance 16z<distance 15z.

As the elongated light exit window plate or diffuser plate 16 has a width 16z, which is larger than a width 14z of the elongated light exit opening 14, but smaller than a distance 15z between longitudinal mounting slots 15a-15b facing each other, an easy top-down mounting by means of tilting of the elongated light exit window plate 16 in the elongated fixture housing 11 is possible, and the usual sliding in technique is no longer necessary. These mounting steps are shown in FIGS. 3 and 4.

As shown in the Figures, one of the flanges 15a2 (15b2) of each longitudinal mounting slot 15a (15b) located closest to the base part 11c of the elongated fixture housing 11 is longer than the other flanges 15a1 (15b1), which is facing furthest from the base part 11c and is facing the area in which the lighting luminaire is to be installed.

Accordingly, using a tilting technique as shown in FIG. 3, one of the first (or second) longitudinal plate edge 16a (16b) of the diffuser plate 16 can be inserted in a corresponding one of the mounting slots 15a (15b). The longitudinal plate edge 16a (16b) rests on the flange 15a2 (15b2). As the width 16z of the diffuser plate 16 is smaller than the distance 15z between both longitudinal mounting slots 15a-15b, the diffuser plate 16 can be placed with its other plate edge 16b (16a) in a resting manner on the other flange 15b2 (15a2) of the other longitudinal mounting slot 15b (15a), see FIG. 4.

Thus, the assembly of the lighting luminaire 10 according to the disclosure is less cumbersome, either at the assembly line (which now can have a reduced footprint) as well as on-site for maintenance or replacement purposes.

For fixating the elongated light exit window plate or diffuser plate 16 within the longitudinal mounting slots 15a-15b, a set of two fixating plate elements 17-1 and 17-2

is used. Each fixating plate element 17-1 and 17-2 interacts with one of the two frontal plate edges 16c-16d of the elongated light exit window plate 16. See FIGS. 1, 6 and 7. In particular, each fixating plate element 17-1 and 17-2 has first and second longitudinal element edges 17a-17b. Furthermore the thickness of the fixating plate element 17-1 and 17-2 is smaller than the distance between the two flanges 15a1-15a2 (15b1-15b2). Preferably, the thickness of the fixating plate elements 17-1 and 17-2 is the same as the thickness of the elongated light exit window plate 16.

Therefore, each first and second longitudinal element edge 17a-17b can be accommodated in one of the two longitudinal mounting slots 15a-15b. Each fixating plate element 17-1 and 17-2 has a frontal (proximal) element edge 17c, which proximal element edge 17c, when the fixating plate element 17-1 and 17-2 is mounted in the mounting slots 15a-15b, is facing a frontal plate edge 16c-16d of the elongated light exit window plate 16. A distal element edge 17d of each fixating plate element 17-1 and 17-2 is facing the opposite direction pointing away from the elongated light exit window plate 16.

It is preferred that the two fixating plate elements 17-1 and 17-2 together with the elongated light exit window plate 16 have a combined length, which is equal to the length of the light exit window 14 of the lighting luminaire 10. The fixating plate elements 17-1 (17-2) with the diffuser plate 16 in between can be held in place between the longitudinal mounting slots 15a-15b by means of so-called endcaps (not shown). Such endcaps can be placed over the two opposing end faces of the whole lighting luminaire 10 and abut against the distal element edges 17d of each fixating plate element 17-1 and 17-2. The abutting action clamps the endcaps against the two fixating plate elements 17-1 and 17-2 and accordingly clamps the elongated light exit window plate 16 in between.

The clamping action exerted in the longitudinal orientation of the light exit window 14 causes the profiled complementary edges 17c and 16c-16d to interface or align with each other, resulting in a proper immobilizing and centering of the elongated light exit window plate 16 between the longitudinal mounting slots 15a-15b. This ensures an overall covering of the light exit window 14 without exposed light slits. The clamping action caused by the endcaps also prevents an undesired dislodging of the elongated light exit window plate 16 from the longitudinal mounting slots 15a-15b and from the lighting luminaire 10 accordingly.

Each proximal element edge 17c of both fixating plate elements 17-1 and 17-2 is structured to fixate the elongated light exit window plate 16 between the two longitudinal mounting slots 15a-15b. The fixation is achieved through abutment against a corresponding frontal plate edge 16c-16d of the elongated light exit window plate 16. In short, both fixating plate elements 17-1 and 17-2 clamp the elongated light exit window plate 16 inside the mounting slots 15a-15b.

Accordingly, through abutment at the frontal plate edges 16c-16d with the two fixating plate elements 17-1 (17-2), it is prevented that the diffuser plate 16 can dislodge from the longitudinal mounting slots 15a-15b. No use of additional fixing parts, for example screws or brackets is required. Also it is not necessary to design and manufacture diffuser plates with complex snap fit interfaces by means of extrusion.

In a preferred example and as shown in more detail in FIGS. 7 and 8 (8A-8D), the fixating plate element 17-1 (17-2) has a width 17z, which is slightly larger than the width 16z of the elongated light exit window plate 16. Similarly, in order to allow a proper accommodation

between the two mounting slots **15a-15b**, its width **17** is smaller than the distance **15z** between the longitudinal mounting slots **15a-15b** facing each other (between both base faces **15a3** and **15b3**). These dimensions as well as the abutment principle allows a proper centering of the elongated light exit window plate **16** between the longitudinal mounting slots **15a-15b**. This ensures an overall covering of the light exit window **14** without exposed light slits. It also prevents an undesired dislodging of the elongated light exit window plate **16** from the longitudinal mounting slots **15a-15b** and from the lighting luminaire **10** accordingly.

Each fixating plate element **17-1** (**17-2**) can have a width **17z**, which is equal to the distance **15z** between the longitudinal mounting slots **15a-15b** facing each other. Also this guarantees a proper centering of the fixating plate elements **17-1** (**17-2**) within the mounting slots **15a-15b** and relative to the elongated light exit window plate **16**.

The proximal element edge **17c** of each fixating plate element **17-1** (**17-2**) is provided with a specific profile **18**, which is interacts through abutment with a corresponding, yet complementary profile **19** provided at each frontal plate edge **16c-16d** of the diffuser plate **16**. Preferably, the profiles **19** provided at each frontal plate edge **16c-16d** of the light diffuser plate **16** are identical to each other, further simplifying the manufacturing thereof through sheet cutting and for symmetrical assembly purposes. In particular, the profiled proximal element edge **17c** and the profiled frontal plate edges **16c-16d** are symmetric along a longitudinal direction of either fixating plate element **17-1** (**17-2**) and elongated light exit window plate **13**. Herewith the assembly of both the fixating plate elements and the elongated light exit window plate is simplified, and its mounting can be achieved irrespective of their side orientation. Using complementary profiles **18** and **19** on both abutting frontal (proximal) element edges **17c** and frontal plate edges **16c-16d** of the elongated light exit window plate **16** ensures a proper abutment over the full width dimension of both parts thereof, thus guaranteeing an effective and durable fixating and centering relative to the mounting slots **15a-15b**.

Each profile **18** (**19**) can consist of extensions **18a** (**19a**), which interact with complementary recesses or chamfers **19b** (**18b**). In other examples, the profiles **18** and **19** can have a partly spherical configuration, which are complementary to each other.

Examples of certain profiles **18** and **19** provided at the proximal element edges **17c** and frontal plate edges **16c-16d** of both the fixating plate elements **17-1** (**17-2**) and the elongated light exit window plate **16** are shown in FIGS. 6, and 8A-8D.

The example of FIGS. 6, 7 and 8A show a profile **18** of the proximal element edges **17c** with three extensions **18a**, one extension positioned in the middle (at the longitudinal axis of the fixating plate elements **17-1** (**17-2**)) and two at either first and second longitudinal element edge **17a-17b**. Similarly, a complementary profile **19** provided at frontal plate edges **16c-16d** of the elongated light exit window plate **16** consists of a centre recess **19b** positioned in the middle (at the longitudinal axis of the elongated light exit window plate **16**) and two chamfered corners **19b** at each first and second longitudinal plate edge **16a-16b**. Thus, profile **18** nicely fits or meshes to complementary profile **19** when proximal element edge **17c** abuts with frontal plate edge **16c** (or **16d**), resulting in a centering of the diffuser plate **16** between the mounting slots **15a-15b**.

The example of FIG. 8B depicts a simpler, but also effective alternative wherein the centre extension and centre recess of both profiles are omitted. The profiled frontal plate

edge has a fully convexly shaped profile **19** and the profiled frontal element edge has complementary concave profile **18**.

In particular, the profiles **18-19** as depicted in FIGS. 6, 7, 8A and 8B having extensions at either first and second longitudinal element edge **17a-17b** and two chamfered corners **19b** at each first and second longitudinal plate edge **16a-16b** allow a fixation of the elongated light exit window plate **16** between the two longitudinal mounting slots **15a-15b** through abutment against both longitudinal plate edges **16a-16b**.

In FIG. 8C, profiles **18** and **19** are used which are shaped as complementary saw-tooths having teeth **18a-19a** and valleys **18b-19b**, which mesh with each other through abutment.

In FIG. 8D, profiles **18** and **19** are used which are shaped as complementary extending curved shapes **19a** and receding curved bowl or basin shapes **18b**, which likewise mesh with each other through abutment, resulting in a centering of the diffuser plate **16** between the mounting slots **15a-15b**. The curved shapes can be configured as complementary semi-circles as shown in FIGS. 8D, yet other curvatures are feasible, such as elliptical, polynomial or sinusoid.

For cost effective reasons as well for ensuring uniform optic features, the fixating plate elements **17-1** and **17-2** and the elongated light exit window plate **16** are made from the same light transmissive material. Accordingly, the light emission from the lighting luminaire **10** is not different for the separate elements, which cover the light exit window, further improving its overall appearance to a user. Examples of plastic materials typically used for light diffusers are polycarbonate, PMMA (poly-methyl methacrylate), polystyrene. As an alternative material, quartz or glass can be used.

Alternatively, the fixating plate elements **17-1** and **17-2** and the elongated light exit window plate **16** can have different light transmissive characteristics. For example, the fixating plate elements **17-1** and **17-2** can be made less transparent to light due to an additive added to the plastic material, such as a dye. In such example, the fixating plate elements **17-1** and **17-2** can have a white "milky" appearance, yet in another non-transparent example the fixating plate elements **17-1** and **17-2** can be black to reduce light transmission.

In addition, certain optical structures can be applied on the surface of either the fixating plate elements **17-1** and **17-2** and the elongated light exit window plate **16** or on both, for example comprising satin structures, various micro lens structures or beam shaping structures.

Finally, FIG. 7 shows with reference numeral **20** a kit of parts comprising an elongated light exit window plate **16** and at least two fixating plate element **17-1** and **17-2**, all parts having complementary profiles **18-19** and the correct dimensions, such their widths **16z** and **17z** and combined length dimension, depending on corresponding dimensions such as the width **14z** and length of the light exit window **14** and the distance **15z** between the mounting slots **15a-15b** of a suitable lighting luminaire.

Such kit of parts can be used for the on-site replacement of for example slide-in diffusor plate of an already installed lighting luminaire.

LISTING OF REFERENCE NUMERALS USED

10 lighting luminaire

11 elongated fixture housing

11a-11b first and second side parts of elongated fixture housing

11c base part of elongated fixture housing

- 12 light emitting element
  - 13 power electronics/power circuitry
  - 14 elongated light exit opening
  - 14z width of elongated light exit opening
  - 15a first longitudinal mounting slot
  - 15a1-15a2 flanges of first mounting slot
  - 15a3 base face of first mounting slot
  - 15b second longitudinal mounting slot
  - 15b1-15b2 flanges of second mounting slot
  - 15b3 base face of second mounting slot
  - 15z distance between base faces of longitudinal mounting slots
  - 16 elongated light exit window plate (diffuser plate)
  - 16a-16b first and second longitudinal plate edge of elongated light exit window plate
  - 16c-16d first and second frontal plate edge of elongated light exit window plate
  - 16z width of elongated light exit window plate
  - 17-1; 17-2 first and second fixating plate element
  - 17a-17b first and second longitudinal element edge of fixating plate element
  - 17c profiled frontal (proximal) element edge of fixating plate element
  - 17d distal element edge of fixating plate element
  - 17z width of fixating plate element
  - 18 profile of profiled frontal element edge
  - 19 complementary profile of profiled frontal plate edge
  - 18a-19a protrusion/extension
  - 18b-19b recess/chamfer
  - 20 kit of parts 16 and 17-1 and 17-2
  - 21 substrate
- The invention claimed is:
1. A lighting luminaire, in particular for a suspended tile light ceiling assembly, the lighting luminaire at least comprising:
    - an elongated fixture housing comprising an elongated light exit opening; and
    - an elongated light exit window plate structured to be mounted to the fixture housing for covering the elongated light exit opening, wherein
    - the elongated light exit opening is bound by two longitudinal mounting slots facing each other, the longitudinal mounting slots each being configured to accommodate a longitudinal plate edge of the elongated light exit window plate, wherein
    - the elongated light exit window plate has a width larger than a width of the elongated light exit opening, but smaller than a distance between longitudinal mounting slots facing each other, and
    - the lighting luminaire further comprising a set of two fixating plate elements, each fixating plate element having two longitudinal element edges each structured to be accommodated in one of the two longitudinal mounting slots and a frontal element edge structured to

- fixate the elongated light exit window plate between the two longitudinal mounting slots through abutment against a frontal plate edge of the elongated light exit window plate
- 5 wherein the frontal element edge is further structured to fixate the elongated light exit window plate between the two longitudinal mounting slots through abutment against both longitudinal plate edges of the elongated light exit window plate, and
- 10 wherein the fixating plate element has a width larger than the width of the elongated light exit window plate.
- 2. The lighting luminaire according to claim 1, wherein the fixating plate element has a width smaller than the distance between the longitudinal mounting slots facing each other.
- 15 3. The lighting luminaire according to claim 1, wherein the fixating plate element has a width equal to the distance between the longitudinal mounting slots facing each other.
- 4. The lighting luminaire according to claim 1, wherein the fixating plate element has a non-linear profiled frontal element edge across its entire width that is complementary to a profiled frontal plate edge of the elongated light exit window plate.
- 25 5. The lighting luminaire according to claim 4, wherein the profiled frontal element edge and the profiled frontal plate edge are symmetric along a longitudinal direction of either fixating plate element and elongated light exit window plate.
- 30 6. The lighting luminaire according to claim 4, wherein the profiled frontal element edge or the profiled frontal plate edge is partly or fully convexly profiled and the profiled frontal plate edge or the profiled frontal element edge is complementary concavely profiled.
- 35 7. The lighting luminaire according to claim 4, wherein the profiled frontal element edge or the profiled frontal plate edge is provided with at least two protrusions and the profiled frontal plate edge or the profiled frontal element edge is provided with at least two complementary recesses.
- 40 8. The lighting luminaire according to claim 1, wherein the fixating plate element and the elongated light exit window plate are made from the same light transmissive material.
- 45 9. The lighting luminaire according to claim 1, further comprising at least one light emitting element accommodated in the elongated fixture housing.
- 10. The lighting luminaire according to claim 9, wherein the elongated fixture housing is provided with power electronics for supplying power to the at least one light emitting element.
- 50 11. A kit of parts comprising an elongated light exit window plate and at least two fixating plate elements according to claim 1.
